UNITED STATES PATENT OFFICE.

CHARLES W. DUBEN, OF MANITOWOC, WISCONSIN.

MACHINE FOR SANDING MOLDINGS.

Application filed February 15, 1926. Serial No. 88,317.

This invention relates to sanding machines and is particularly directed to a machine for sanding molding.

Objects of this invention are to provide a machine which will automatically sand molding or other strips of unusual shape in a rapid and effective manner, and which will feed the strips through the machine without requiring any attention from the operator so that each portion of the strip is thoroughly sanded.

Further objects are to provide a sanding machine in which a reciprocatory shoe is provided with a yielding bottom portion contoured to fit the molding and in which clamping means are provided for holding the sand paper wrapped about the yielding portion of the shoe.

Further objects are to provide a sanding machine in which the feeding and supporting mechanism is carried by a table and driven from or operatively connected to the reciprocatory mechanism, and to provide supports for the table which will lower the table and to permit changing of shoes or supports without requiring any alteration of the operative connection between the reciprocatory means and the feeding means.

Embodiments of the invention are shown in the accompanying drawings, in which:—

30 Figure 1 is a vertical sectional view through the machine, such view corresponding to a section in the line 1—1 of Figure 3.

Figure 2 is a transverse sectional view corresponding to a section on the line 2—2 of Figure 3.

Figure 3 is a transverse vertical sectional view on the line 3—3 of Figure 1.

Figure 4 is a view of a modified form of reciprocatory head.

40 Figure 5 is a sectional view on the line 5—5 of Figure 4.

Referring to the drawings, particularly Figures 1 to 3, it will be seen that the machine comprises a main frame 1 in which a table 2 is slidably mounted. This table is provided with slanting parallel flanges 3 which co-operate with the slanting flanges on guides 4 of the main body portion 1 so that when the table is lowered, it will travel down-

wardly and rearwardly. The position of the table is controlled by means of the wide cams 5 which are mounted upon parallel shafts 6. These shafts carry worm wheels 7 which mesh with worms 8 carried by the hand wheel shaft 9. The hand wheel shaft extends through the body of the machine and is provided with a manipulating hand wheel 10 at its outer end.

The table carries a sub-base 11 which is bolted thereto as shown in Figures 1 and 2, and the sub-base is provided with an upright standard 12 on opposite sides and on each end. These standards carry between them the knurled or fluted feeding rollers 13 which are mounted upon the shafts 14. These rollers engage the under side of the molding or other strip 15. The upper side of the molding is engaged by the resilient rollers 16. These rollers are preferably made of a yielding material such as rubber, for instance, to prevent damaging the finished side of the molding. They are adjustably carried by the standards 12 as shown in Figure 1 so that the exact pressure desired may be had by suitably turning the adjusting screws 17, such screws controlling the position of the bearings for the ends of the shafts of the rollers 16.

Between the standards 12, a molding guide 18 is positioned and is bolted to the sub-base 11 as shown in Figures 1 and 2. This guide as may be seen from Figure 3 is channelled to conform to the contour of the molding.

Referring to Figures 1 and 3, it will be seen that a pair of inwardly curved uprights 19 are positioned upon opposite sides of the mechanism which has been described, so that they form an arch over such mechanism. Their upper ends are spaced apart and receive the sliding head 20 and the reciprocatory shank 21 of the shoe. This head is provided with bottom flanges 22 and a top plate 23 is secured to the head by means of the bolts 24 as shown in Figure 1. The plate 23 and the flanges 22 are positioned upon opposite sides of the guides 25 of the members 19 as most clearly brought out in Figure 3. It is to be noted from reference to Figure 1 that the sliding head has an extensive elongated bearing with reference to the guiding portion of

the machine, and consequently will hold the shank 21 in its correct position although permitting free reciprocatory motion thereof.

It is to be noted particularly from Figure 1 that the shank 21 is provided with outwardly projecting ears or lugs 26 and has a flat bottomed face. The shoe proper consists of a metal bar 27 to which is cemented, or otherwise secured, the curved rubber shoe 28. This 10 shoe 28 is contoured to fit the molding and is securely cemented as stated, or secured by other means, to the metal bar 27. The bar 27 is secured to the lugs 26 of the shank by means of bolts 29. The metal bar 28 projects 15 outwardly and is apertured at its ends to receive the clamping bolts 30; such clamping bolts passing through the ends of the clamp strips 31.

In the actual operation of this device, a 20 sheet of sand paper 32 is wrapped about the shoe 28 and extends upwardly on opposite sides thereof, and also if of sufficient extent, on opposite sides of the shank 21. It passes beneath the clamping strips 31 and is thus securely held in place. The upper portion of the sand paper sheet 32 may be held by means of spring clips 33 secured to the outer side faces of the shank 21.

Any suitable means may be employed for 30 reciprocating the shoe. For instance, the slide 20 may be connected by means of a pitman 34 with a crank 35, such crank being preferably carried by a fly wheel 36, such fly wheel in turn being mounted upon the shaft 37. This fly wheel may also be the wheel upon which the driving belt is carried and through which power is transmitted to the machine. The shaft 37 carries a sprocket wheel 38 which is connected by means of a 40 chain 39 with a sprocket wheel 40. See Figures 1, 2, and 3. The sprocket wheel 40 is rigid with a smaller sprocket wheel 41 which is connected by means of a chain 42 with sprocket wheels 43 carried by the shafts 14 of the feed rollers.

Thus when the driving pulley or flywheel 36 is rotated, the shoe is reciprocated and the molding is fed at a uniform rate through the machine.

50 When it is desired to lower the table 2, as for instance, to provide room for changing the support or guide 18 for the molding or for changing the shoe, it is merely necessary to rotate the hand wheel 10, thus, rotating 55 the cams 5 and lowering the table in a rearwardly slanting direction. The side flanges of the table 2 are slotted as indicated in 44 whereby spaces for the cam shafts 6 are provided. The purpose of the rearwardly slanting direction for the table is to avoid the necessity of throwing off the sprocket chain 39 when the table is adjusted. The downward travel of the table would tighten the chain 60 except for the fact that the table travels rear-

wardly at the same time, thus preventing 65 tightening of such chain. In this manner all of the parts may be left operatively coupled together and the table lowered for interchanging or adjustment of the several parts.

In the modified form shown in Figure 4, 70 the same type of shank 21 is illustrated. This shank, however, carries a frame 45 which is provided with curved slots 46 through which attaching bolts 47 pass. These attaching 75 bolts 47 as more clearly shown in Figure 5 are provided with heads 48 which are enlarged and which slide within the slots 49 formed in the auxiliary shoes 51 which in turn carry sand paper as previously described. The main shoe 28 also carries sand paper and operates in a manner identical with that previously described.

It is to be noted particularly that with this 80 form of device two frames 45 are provided, one at each end of the shank 21 and that between these frames auxiliary shanks carrying auxiliary shoes are adjustably positioned. Thus it is possible with this form of the invention to operate upon molding having a plurality of channels, protuberances or any 90 other unusual contours.

Further, it will be seen that the machine 95 may be used with a single shoe as first described and when other work comes to the machine, it is merely necessary to attach the frames 45 to the main shank, thus adapting the machine to the new work.

It will be seen that a very simple sanding machine has been provided, and one in which the operation of feeding and sanding the 100 molding is wholly automatic and does not require the supervision of an operator.

Although the invention has been described in considerable detail, such description is intended as illustrative rather than limiting as 105 the invention may be variously embodied and as the scope of such invention is to be determined as claimed.

I claim:

1. A sanding machine comprising a table, 110 means for feeding and guiding a strip of material across said table, a shank mounted for reciprocation across said table, a frame carried by said shank and having arcuate slots therein, a plurality of shoes adapted to carry 115 abrasive material, and bolts passing through said slots and engaging said shoes, whereby said shoes may be bodily shifted and guided by said arcuate slots.

2. A sanding machine comprising a table, 120 means for feeding and guiding a strip of material across said table, a shank mounted for reciprocation across said table, a frame carried by said shank and having arcuate slots therein, a plurality of shoes adapted to carry 125 abrasive material, and bolts passing through said slots and having heads, said shoes having slots extending lengthwise of the shoes

for receiving said bolts, whereby said shoes may be bodily shifted and guided by said arcuate slots.

3. A sanding machine comprising a table, means for feeding and guiding a strip of material across said table, a shank mounted for reciprocation across said table, a frame carried by said shank and having arcuate arms, a plurality of shoes for carrying abrasive ma-

terial, and bolts adjustably connecting the 10 shoes with said arms whereby said shoes may be bodily shifted and guided by said arms.

In testimony that I claim the foregoing I have hereunto set my hand at Manitowoc, in the county of Manitowoc and State of Wis- 15 consin.

CHARLES W. DUBEN.
